UNITED STATES PATENT OFFICE

2,207,596

REFRIGERATING APPARATUS

Edward B. Newill, Dayton, Ohio, assignor to General Motors Corporation, Dayton, Ohio, a corporation of Delaware

Application April 25, 1936, Serial No. 76,438

5 Claims. (Cl. 62—108.5)

This invention relates to liquid congealing apparatus and particularly to a tray structure having a grid therein for forming ice blocks suitable for table use.

5 It is an object of my invention to provide an improved tray structure for congealing or freezing liquids.

Another object of my invention is to provide an improved flexible metallic ice tray for use in refrigerating apparatus.

10 A further object of my invention is to provide a metallic ice tray having resilient walls that can be flexed to break the bond between ice in the tray and the tray walls to thereby facilitate removal of ice therefrom and to provide a novel device for flexing the resilient tray walls.

15 Further objects and advantages of the present invention will be apparent from the following description, reference being had to the accompanying drawings wherein a preferred form of the present invention is clearly shown.

In the drawings:

20 Fig. 1 is a top plan view of an ice tray constructed in accordance with the present invention;

25 Fig. 2 is a sectional view taken on the line 2—2 of Fig. 1 showing in elevation a device for flexing the tray walls in associated position with the tray;

30 Fig. 3 is a top plan view of the tray disclosed in Fig. 1 showing the walls of the tray after being flexed by the device disclosed in Fig. 2;

35 Fig. 4 is a sectional view similar to Fig. 2 and is taken on the line 4—4 of Fig. 3 showing the tray walls in a position after having been flexed by the flexing device; and

40 Fig. 5 is an enlarged top plan view of a portion of the tray to more clearly show the walls thereof flexed outwardly away from ice contained therein.

45 Referring to the drawings for a detailed description of the invention, numeral 10 designates generally a tray preferably formed of resilient or flexible metal such, for example, as stainless steel, since this material is a good conductor of heat, is highly flexible and is non-corrosive. The tray 10 is of the type adapted to be placed in or on a cooling element of a refrigerating system and adapted to contain a grid of any suitable or conventional construction for dividing the interior thereof into a plurality of open top compartments so that water placed in the tray will be frozen into ice blocks. I am aware of the fact that flexible rubber trays have been employed for use 50 with refrigerating apparatus, but these rubber

trays have not been entirely satisfactory due to the long time required to freeze the contents thereof. Obviously, therefore, a metal tray with a metal grid therein is more desirable for such use. While I have described the tray of the present invention as having a conventional grid disposed therein, it is to be understood that any type of grid may be disposed in the tray. For example, grids of the type shown in the patents to Jules N. Saler No. 2,037,518, No. 2,037,519, and No. 2,037,521, dated April 14, 1936, which are constructed in a manner so as to be flexible after removal thereof from a tray to facilitate the removal of ice blocks therefrom without application of heat to the grid, may be used in combination with my improved tray.

55 The tray 10 of the present invention is preferably formed by being drawn from a flat sheet of resilient stainless steel to provide a bottom wall 11 and upstanding side and end walls 12. The upper extremity 13 of the walls 12 is folded over as at 14 to provide rigidity along the top of the tray. The resiliency of the walls 11 and 12 is such that they normally retain a predetermined bowed position even when the tray is filled with water or other substance to be frozen. It will be noted that the resilient bottom wall 11 is formed so as to retain a slightly bowed upward position as shown in Fig. 2 of the drawings while the side and end walls 12 are formed so as to retain an inwardly bowed position as shown in Fig. 1. A unitary grid 16 placed in tray 10 to divide the interior thereof into a plurality of open top molds or compartments includes a vertically disposed longitudinal partition 17 and a plurality of transverse partitions 18. The transverse partitions 18 nearest the central part of grid 16 are made shorter than partitions 18 near the ends of the grid so as to cause the grid to conform to the planar contour of the space between the tray walls 12. The bottom portion or edges of the grid 16 are cut on a curve to conform to the slightly curved contour of the tray bottom 11. Thus, it will be apparent that the bottom and the side edges of the grid 16 fit closely adjacent the walls of tray 10 when the tray is in its normal or predetermined retained position as shown in Figs. 1 and 2. The side walls 12 of tray 10 are each provided with an outwardly directed portion 19 which extends from the top rolled-over edge 14 thereof downwardly to a point slightly above the top edge of grid 16. These portions 19 are located half-way between the ends of the tray 10 and are positioned directly opposite one another. The outwardly directed portions 19 form 55

guiding grooves for receiving the arms or legs of an expansion or flexing device, generally represented by the reference character 21, utilized for a purpose to now be described.

5 The expansion device 21 comprises a pair of legs or arms 22 pivotally mounted upon a pin or shaft 23. The pin or shaft 23 passes through and is secured to a bracket member 24 which has a knob or handle portion 25 mounted thereon or 10 if desired formed integral therewith. The device 21 is shown in Figs. 1 and 2 as being in a position adapted to have force applied thereto for expanding the resilient walls 11 and 12 of tray 10 outwardly from ice in the tray, but it is to be 15 understood that the device 21 is normally detached or removed from the tray. Assuming that the contents of the tray have been frozen, the tray removed from the cooling element of a refrigerating system and the device 21 moved into 20 association with the tray with the legs or arms 22 thereof fitting in the grooves provided by the outwardly directed portions 19 on tray 10 then a downward force applied to the knob or handle 25 will move the legs or arms 22 thereof outwardly 25 and such movement will flex the side walls 12 of tray 10 outwardly from the frozen contents of the tray to break an ice bond therebetween. The construction of tray 10 and the resilient characteristics of the bowed metal walls thereof are such 30 that, when the operation just described is being carried out, the end walls of the tray tend to move outwardly relative to ice in the tray to thus peel the end walls therefrom. Due to the curved or bowed formation of the bottom wall 11 of tray 35 10, it is inherent in the structure disclosed that this bottom wall will also be flexed out of its normal position or moved away from ice in the tray after the side walls have been loosened. This movement or flexed position of the resilient walls 40 11 and 12 of tray 10 is clearly illustrated in Figs. 3, 4 and 5 of the drawings.

By referring to Figs. 3, 4 and 5, it will be noted that there is a space 26 along and between the ice in tray 10 and its flexed side walls 12, a space 45 27 along and between the ice in tray 10 and its flexed end walls 12 and a space 28 along and between the ice in tray 10 and its flexed bottom wall 11, thereby illustrating the separation of the tray walls from the ice. All of the metal walls 50 of tray 10 are thus substantially peeled away from ice frozen in the tray to thereby permit removal of the ice along with grid 16 therefrom without application of heat to the tray. After the ice bond between walls of the tray 10 and 55 ice therein has been broken, the device 21 is removed or detached from the tray and tray is then inverted to permit the ice together with grid 16 to fall or slide out of the tray. After the ice and the grid 16 have been removed from the tray 60 10, the ice may be removed or harvested from grid 16 in any suitable or desirable manner. It is to be understood that the walls of the tray will, after device 21 has been detached therefrom, move or spring back into their normal predetermined position, but this position of the tray walls 65 does not interfere with removal of ice from the tray because of the fact that the ice bond has been previously broken. While the metallic tray walls are described as being resilient or flexible, 70 they are of sufficient rigidity to withstand the weight of water or other substance placed in the

tray to be frozen without unduly flexing the walls out of their normal predetermined bowed position.

From the foregoing, it will be apparent that I have provided an improved metallic ice tray construction which may be readily and easily manually flexed to remove the frozen contents therefrom, thus eliminating the necessity of applying heat in the form of warm water, for example, to the tray to cause removal of its frozen contents. My improved tray and the method of removing ice therefrom as described permits the ice to retain latent heat stored therein and renders the ice blocks removed therefrom more efficient in cooling drinks, etc. 15

While the form of embodiment of the invention as herein disclosed, constitutes a preferred form, it is to be understood that other forms might be adopted, all coming within the scope of the claims which follow. 20

What is claimed is as follows:

1. An ice tray having resilient metallic side, end and bottom walls, said side walls being normally slightly bowed inwardly, said tray being constructed and arranged so that an outward pressure when applied to an intermediate point of each of said side walls will spread said side and end walls, respectively, apart and thereby break an ice bond between said tray walls and ice contained therein. 25

2. An ice tray having resilient metallic side, end and bottom walls, all of said walls being normally slightly bowed, said tray being constructed and arranged so that an outward pressure when applied to an intermediate point of each of said side walls will spread the side walls apart and flex the bowed bottom and end walls to thereby break an ice bond between said tray walls and ice contained therein. 30

3. An ice tray having a resilient metallic bottom wall, opposed resilient metallic upright side walls and opposed resilient metallic upright end walls, said side and said end walls being normally slightly bowed inwardly, said tray being constructed and arranged so that an outward pressure when applied to an intermediate point of each of certain of said opposed upright bowed walls will spread same apart and flex each of the other of the opposed upright bowed walls and the resilient tray bottom wall to thereby break an ice bond between said tray walls and ice contained therein. 40

4. An ice tray having resilient metallic side, end and bottom walls, said side walls being normally slightly bowed inwardly, means associated with the tray for applying an outward pressure to an intermediate point of each of said side walls to spread said side and end walls, respectively, apart and thereby break an ice bond between said tray walls and ice contained therein. 55

5. An ice tray having resilient metallic side, end and bottom walls, said side walls being normally slightly bowed inwardly, expansible means associated with the tray and having a part thereof engaging an intermediate point of each of said side walls for applying an outward pressure there-to to spread said side and end walls, respectively, apart and thereby break an ice bond between said tray walls and ice contained therein. 65
